US00D825174S

(12) **United States Design Patent** (10) **Patent No.:** **US D825,174 S**
(45) **Date of Patent:** **** Aug. 14, 2018**

(54) **KNITTING NEEDLE**

(71) Applicant: **William Prym GmbH & Co. KG**,
Stolberg (DE)

(72) Inventor: **Andreas Papenfuss**, Weimar (DE)

(73) Assignee: **William Prym GmbH & Co. KG**,
Stolberg (DE)

(**) Term: **15 Years**

(21) Appl. No.: **29/592,054**

(22) Filed: **Jan. 26, 2017**

(30) **Foreign Application Priority Data**

Aug. 9, 2016 (EM) 003 335 363

(51) **LOC (11) Cl.** **03-01**

(52) **U.S. Cl.**

USPC **D3/18**

(58) **Field of Classification Search**

USPC D3/18, 20, 28; D15/66, 78; D24/130

CPC D04B 3/00; D04B 3/02; D05B 85/00

See application file for complete search history.

(57) **CLAIM**

The ornamental design for a knitting needle, as shown and described.

DESCRIPTION

FIG. 1 is a front view of a knitting needle showing the new design;

FIG. 2 is a back right perspective view thereof;

FIG. 3 is a back left perspective view thereof;

FIG. 4 is a rearview thereof;

FIG. 5 is a top view thereof;

FIG. 6 is a bottom view thereof;

FIG. 7 is a front right bottom perspective view thereof; and, FIG. 8 is a back left bottom perspective view thereof.

1 Claim, 2 Drawing Sheets
